COMBINED UTILITY CASE AND KEY RING

Wayne J. Watts, Box 303, Millville, Pa. 17846

Filed Aug. 1, 1974, Ser. No. 493,925

Term of patent 14 years

Int. Cl. D2—99

U.S. Cl. D2—400

Fig. 1.

Fig. 2.

FIG. 1 is a front elevational view of a combined utility case and key ring showing my new design, the rear being substantially a mirror image but flat and plain; and

FIG. 2 is a right side elevational view thereof, the left side being substantially a mirror image but with the key ring and snap obscured.

I claim:

The ornamental design for a combined utility case and key ring, substantially as shown and described.
